UNITED STATES PATENT OFFICE.

JEAN BAPTISTE VERDIER, OF PARIS, EMPIRE OF FRANCE.

IMPROVED MARINE LIFE-PRESERVER.

Specification forming part of Letters Patent No. 41,654, dated February 16, 1864.

To all whom it may concern:

Be it known that I, JEAN BAPTISTE VERDIER, of Paris, in the Empire of France, have invented certain new and useful Improvements in Life-Belts; and I do hereby declare the following to be a full, clear, and exact description of the same, reference being had to the accompanying drawings, and to the letters of reference marked thereon.

My improved life-belt consists of two pads containing buoyant material, in combination with certain cords, an adjustable strap, and a neck-yoke, the whole being constructed and arranged for attachment to the body, as described hereinafter, so as to effectually buoy up the wearer in the water, and at the same time leave his arms at liberty.

My invention further consists in combining with the said pad a neck-strap, by the aid of which the life-belt is prevented from being displaced.

In order to enable others to make and apply my invention, I will now proceed to describe the manner of constructing and using the same.

On reference to the accompanying drawings, which form a part of this specification, Figure 1 is a front view of my improved life-belt; Fig. 2, a plan view, and Fig. 3 an end view.

Similar letters refer to similar parts throughout the several views.

A and B are two pads or cushions of the form or approximating to the form represented in the drawings, and consists of two bags of suitable fabric packed with such substance as will make them of the desired buoyancy. The pad A is furnished at each end with projections c, to eyelets in which are secured the ends of cords d, which pass through projections or ears on the pad B. In front of the pad A, and partly overlapping the ends of the same, is a strap, e, which passes through sta-

ples or guide-pieces o, attached to the said pad, one end of the strap being secured to the cords d at one end of the life belt, and other to the similar cords, d, at the opposite end of the belt. The strap e is provided with a suitable buckle, f, by means of which the strap may be shortened or lengthened, as desired, and the pads A and B be brought nearer to or removed farther from each other.

To the pad B are secured the two straps s and s', which are connected together by the cord or band g.

In applying the life-belt or life-preserved to the body the inside of the pad A is placed against the chest and the inside of the pad B against the back. The band or cord g is placed over the head and around the neck. The strap e is then tightened so as to cause the pads A and B to bear with sufficient force against the body. The belt is then firmly secured, and is prevented from being displaced by the neckband g.

It will be observed that the life-belt is so formed and constructed that while it buoys up the wearer the latter has his arms at liberty.

The pads may be provided with pockets and other appliances for containing food, water, and other articles serviceable in case of shipwreck.

I claim as my invention and desire to secure by Letters Patent—

The pads A and B, containing buoyant material, in combination with the cords d, adjustable strap e, and neckband g, the whole being constructed and arranged for application to the body, as set forth.

In testimony whereof I have signed my name to this specification before two subscribing witnesses.

J. BTE. VERDIER.
